UNITED STATES PATENT OFFICE

122,930

DESIGN FOR A DISPLAY BOX FOR NECK- WEAR, HANDKERCHIEFS, BOUTONNIERES, OR THE LIKE

Benjamin Shapiro, Germantown, Pa.

Application April 20, 1940, Serial No. 91,823

Term of patent 7 years

To all whom it may concern:

Be it known that I, Benjamin Shapiro, a citizen of the United States of America, residing at Germantown, in the county of Philadelphia and State of Pennsylvania, have invented a new, original, and ornamental Design for a Display Box for Neckwear, Handkerchiefs, Boutonnieres, or the like, of which the following is a specification, reference being had to the accompanying drawing, forming part thereof.

Fig. 1 is a perspective view of a display box, showing my new design;

Fig. 2 is a top plan view of the display box; and, Fig. 3 is a top plan view of the display box with the cover removed to show the complete design of the insert within the bottom of the box.

I claim:

The ornamental design for a display box for neckwear, handkerchiefs, boutonnieres, or the like, as shown and described.

BENJAMIN SHAPIRO.
